DESIGN FOR A COMBINED TRANSFORMER AND SIGN FRAME

Leonard C. Marschall, Chicago, Ill., assignor to
Sola Electric Co., Chicago, Ill., a corporation of
Delaware

Application August 29, 1938, Serial No. 79,626

Term of patent 3½ years

To all whom it may concern:

Be it known that I, Leonard C. Marschall, a citizen of the United States, residing at Chicago, in the county of Cook and State of Illinois, have invented a new, original, and ornamental Design for a Combined Transformer and Sign Frame, of which the following is a specification, reference being had to the accompanying drawing, forming part thereof.

In the drawing:

Fig. 1 is a front elevational view of a combined transformer and sign frame embodying my new design;

Fig. 2 is a top plan view thereof;

Fig. 3 is a bottom plan view thereof; and

Fig. 4 is an end elevational view thereof.

I claim:

The ornamental design for a combined transformer and sign frame, substantially as shown.

LEONARD C. MARSCHALL.
